UNITED STATES PATENT OFFICE.

ALBERT AUGUST HASLER, OF HAZLETON, PENNSYLVANIA.

DESIGN FOR TEXTILE FABRIC.

44,531.

Specification for Design.

Patented Aug. 19, 1913.

Application filed May 15, 1913. Serial No. 767,927. Term of patent 8½ years.

To all whom it may concern:

Be it known that I, ALBERT AUGUST HASLER, a citizen of Switzerland, and resident of Hazleton, in the county of Luzerne and State of Pennsylvania, have invented a new, original, and ornamental Design for Textile Fabrics, of which the following is a specification.

The figure is a plan view of a portion of a textile fabric showing my new design.

I claim—

The ornamental design for a textile fabric as shown.

Signed at Hazleton in the county of Luzerne and State of Pennsylvania this 18th day of July A. D. 1913.

ALBERT AUGUST HASLER.

Witnesses:

HENRY PIPPERT,
CONSTANT SCHOLER.
